UNITED STATES PATENT OFFICE

EDWARD KIRBY BOTTLE, OF ELMIRA, NEW YORK, ASSIGNOR TO AMERICAN SALES BOOK COMPANY, LIMITED, OF TORONTO, CANADA, A CORPORATION OF ONTARIO

MANIFOLDING MACHINE

Application filed January 19, 1928. Serial No. 247,969.

This invention relates to improvements in manifolding machines and more particularly in some of its details to improvements in machines embodying a printing mechanism whereby a plurality of copies may be made simultaneously at a single printing impression.

It is a general object of the invention to provide a machine in which one or more of the copies may be made upon a continuous strip which is automatically fed through the machine as for example where a continuous record is desired of the impressions made by the machine or where additional data is to be individually supplied and to provide mechanism whereby this may be accomplished without impairing the efficiency of the machine in making impressions on individual articles such as envelopes.

It is a further object to adapt printing mechanism of a single impression type for use with continuous strips such that the strips will be automatically fed into proper alignment with the printing mechanism as the machine is operated.

It is a further object to provide a mechanism of the character described simple in construction and inexpensive to manufacture and reliable in its operation.

It is a further object to provide a device which if desired may be constructed by the interconnecting into a unitary machine of standard addressing machine with a mechanically separable operating unit whereby the combined machine may be readily operated with ease and efficiency with a minimum of labor and without damage to the addressing machine should it be desired subsequently to use the latter alone.

The invention accordingly comprises the features of construction, combinations of elements, and arrangement of parts, which will be exemplified in the construction hereinafter set forth and the scope of the application of which will be indicated in the claims.

For a fuller understanding of the nature and objects of the invention, reference should be had to the following detailed description taken in connection with the accompanying drawing, in which:

Fig. 1 is a side elevation of a machine embodying this invention;

Fig. 2 is a top plan view thereof on a larger scale, certain of the parts being broken away better to show the construction;

Fig. 3 is a front elevation of the same machine;

Fig. 4 is a detail of the carbon feed;

Fig. 5 is a perspective view of the strip feed and carbon feed mechanism;

Figs. 6 and 7 are an enlarged view of a detail thereof.

In the drawings, the numeral 1 designates generally a stand adapted to support at its upper end a casing 2 carrying the printing mechanism of an addressing machine such as is more fully described in my co-pending application Serial No. 32,019, filed May 22, 1925, now Patent No. 1,733,329, issued Oct. 29, 1929. This may comprise, as shown at 3, means for supporting printing elements 4 and having a presser head 5 carried by an arm 6, pivoted as at 7, to permit the presser head to be brought down into registry with the printing element. This arm may be operated through the medium of a curved link 9 connected by a link 10 to a foot treadle 11. The machine is provided with ribbon supports 13, 14 adapted to carry a printing ribbon between the printing element and the presser head such that by the superposition of an envelope or other sheet upon the printing ribbon above the printing element, the impression may be made upon the envelope by depression of the presser head through the foot treadle 11.

With the type of machine here illustrated, there is provided as at 15, a receptacle for successive printing elements to be fed through the machine and a second receptacle as shown at 16 for the receipt of printing elements which have been used by the machine. The machine is designed automatically for the taking of the printing elements in the receptacle 15 one at a time and feeding them through the machine past the printing point toward the receptacle 16 with each stroke of the presser head. A spring 17 returns the presser head to its elevated position when the treadle is released.

For a more complete disclosure of a feeding mechanism for printing elements and embodying a construction and arrangement similar to the present disclosure, reference is made to the Patent No. 764,660 for an addressing machine issued to J. S. Duncan on July 12, 1904.

The numeral 50 designates a supporting plate carrying at one end a supply receptacle 51 designed to support a supply of a continuous strip of paper which may if desired have printed forms thereon with weakened lines between the forms and control apertures bearing a definite positional relation to the form. This strip is preferably folded back and forth upon itself at the weakened lines into a zigzag formation. It may be composed of one web or a plurality of webs superposed upon each other and interfolded together to make one or more carbon copies as may be desired. I preferably use this arrangement of the paper supply as it permits the forms to lie flat and in compact space relation, but obviously rolls may be utilized if desired. Since the strip may comprise a single web or a plurality thereof, the word will herein be utilized to signify the entire strip whether or not it be composed of a plurality of webs.

The receptacle 51 may be provided with a door 52 hinged as at 53 for the ready insertion of the supply, and the strip itself is carried over the end of the plate 50 passing around a guide roll 54 at the top of the receptacle. The strip is thence carried over the plate 50 through suitable constraining guides 55, 56, 57 and 58 to a feeding mechanism 60 situated at the other end of the plate 50. This feeding mechanism may be carried within a housing 61 carried by the plate 50 at the end remote from the receptacle 51.

The plate 50 is designed to rest upon the upper face 62 of casing 2 with the receptacle 51 upon one side and the housing 61 on the other, and the inner faces 63 and 64 respectively of the receptacle and housing are so spaced as to engage the sides of the casing 2 to assist in holding the plate 50 in proper location. The plate 50 has its central portion as at 65 cut out immediately over the printing position, that is beneath the presser head. The guides 55, 56, 57 and 58 are arranged to carry the strip directly over the printing position and above the printing ribbon thereon.

The feeding mechanism comprises in general a roller 70 journalled in brackets 71 carried by the plate 50 and cooperating discs 72 carried on shafts 73, journalled in the side walls 74 of the feed housing 61. The discs 72 are in alignment with the control apertures in the strip and are designed so that as the discs are rotated, the strip is fed until the control apertures come into registry with the point of contact with the discs and roller 70, whereupon the feeding ceases. Means are provided for again gripping the strip to start

the next feeding operation which means may take the form of lugs 75 fixed upon the disc and adapted to engage the strips at the side of the apertures. These lugs are preferably so positioned that the strips will be firmly gripped just at the close of the feeding operation.

It will be understood that with the mechanism just described, the strip will be fed the distance between successive control apertures with each revolution of the disc, and mechanism is provided to effect such revolution with each operation of the presser head. The discs 72 and the roller 70 may if desired be geared together to insure their movement with the same peripheral speed. This is particularly advantageous where a plurality of strips are employed to insure that they move together.

To operate the disc 72, there is fixed upon the shaft 73 a gear 76 meshing with a gear 77 carried by a shaft 78 also journalled in the side walls 74. Journalled upon the shaft 78 is an arm 79, carrying a pawl 80 adapted to engage a ratchet 81 fixed upon the shaft 78. The direction of this ratchet is such that the arm 79 and gear 77 will be operatively connected together to feed the paper toward the left as seen in Fig. 3, but will be disconnected to permit the movement of the arm in a reverse direction. A spring pressed dog 82 may be arranged to engage the teeth of the gear 81 to prevent retrograde motion thereof and hence to prevent retrograde motion of the feed.

A lever 90 pivoted as at 91 to a bracket 92 supported from the plate 50 has one end thereof as at 93 extending beneath the presser head arm 6 and positioned to be engaged by the latter as it is depressed and having its other end 94 connected by a link 95 to the arm 79, and a spring 96 connects at one end to the arm 94 and at the other end to the housing 61. As will be seen from the drawing, the action from this spring is such that the arm 93 will be urged upwardly by the spring causing the ratchet 81 to engage the pawl 80 to move the strip feed forwardly until the arm 90 engages a stop 97 as shown diagrammatically in dotted outline in Figure 3. Upon the depression of the presser head, the arm 93 is depressed causing the pawl to idle over the ratchet during which time the retrograde movement of the feed is prevented by the dog 82. This idling movement continues until the arm 94 has reached the extreme of its upward travel whereupon the ratchet reengages and is ready for the next feeding movement when the presser head arm is released.

A plurality of pins are provided as shown at 100 mounted in any preferred manner upon the base plate 50 and extending into the pathway of the strips in alignment with the control apertures and between the printing

mechanism and the supply 51. These pins are so situated that when they are in registry with the control apertures of one set of forms, another set of forms is in registry in printing position upon the machine and the control apertures of another set of forms are in registry with the contact between the feed disc 72 and the roller 70. It will be understood that as the strip is fed over the plate 50, the body of the form will ride over the pins 100 until the control apertures come into registry with the pins whereupon the pins will penetrate the apertures and bring the forms to rest with the forms in accurate registry.

Means are provided for subsequently freeing the strips from the pins. This may be conveniently arranged by maintaining the pins in fixed relation in the normal pathway 20 of the strips as defined by the strip guides and subsequently lifting the strips off of the pins. When this form of freeing is utilized, particularly if this lifting be done at a time when the strip itself is held firmly in place 25 either by the feed mechanism itself or by the printing mechanism, the slack incident to raising the strips is furnished by the feed of the strip out of the supply and this permits the apertures to pass the pins at the 30 beginning of the next feeding movement before the strips again become taut.

In the form illustrated, there is provided upon the plate 50 a bracket 101 to which is pivoted a lever 102 having one arm 103 in position to be engaged by the presser head arm when the latter is depressed. A plate 105 extends transversely of the plate 50 and carries slots 106 in registry with and superposed upon the pins 100. This plate is pivoted along one of its edges and is intended to have the strips carried over its upper surface whereby when the plate is rotated about its pivot, it will serve to lift the strips above the upper ends of the pins.

45 The plate 105 has its pivot extended as shown into a crank 108 engaging a slot 109 in the other arm 110 of the lever 102 whereby when the arm 103 is depressed by the presser head arm, the plate 105 is raised to lift the 50 strip from the pins. The mechanism is arranged to normally hold the plate 105 depressed and this may be accomplished by causing the weight of the arm 109 to overbalance the weight of the arm 103.

55 Mounted upon the plate 50 and secured thereto in any preferred manner as by riveting, brazing, etc. and extending longitudinally thereof on each side of the slot 65 is a housing 120 in each of which 60 is journaled a roller 121 for carrying one or more carbon strips and each of these housings has a slotted opening 122 adjacent to the plate 50 and on the side toward the opening 65 whereby the carbon carried upon one 65 of the rolls may be carried through the slots

over the printing position to be wound upon the other roll. It will be understood that these rolls are preferably arranged so that they are detachable from the housings to facilitate the replenishment of the carbon when required. This detachability may be accomplished by providing each of the rollers 121 which are preferably of wood with a recess in the end as shown at 123 while housing 120 is provided at one end with a fixed stud 124 and at the other end with a stud 125 which is pressed inwardly by spring 126. This stud is provided with a wing 127 adapted to enter a cooperating slot in the end of the roller 121. Each of the housings has a handle 128 attached to the corresponding spring pressed stud. This handle permits the movement of the carbon by the turning of the handle and it permits the removal of the carbon roll by pulling the handle outwardly. This facilitates switching the wooden rolls from one housing to the other when the end of the roll is reached. In order to effect this mechanical motion, there may be mounted upon the plate 50 a cylindrical housing 130 carrying a sliding block 131 pressed upwardly by a spring 132 and having its upper limit adjustably determined by a screw 133 locked by a nut 134. The block 131 carries a pin 135 having on one end a pawl face 136 in position to engage teeth 137 on the handle 123 of the adjacent carbon roll while the reverse side of the pin 135 is in position to be engaged by the presser head arm 6 when the latter is depressed. A spring ratchet 139 100 may also be employed to engage the teeth 137 to prevent a reverse feed of the carbon.

Under certain circumstances it may be desired to employ the machine with a plurality of strips, certain of which are devoid of feed control apertures. Such construction is eminently suited to a situation where it is not necessary to have forms printed upon one of the strips or where some other means are employed for maintaining the registry of the forms. In Fig. 6 is illustrated more in detail a construction suitable for the accomplishment of such a result. As will be seen, the pins 100 are carried by a bar 150 which is supported from the side walls of the casing 151 and in spaced relation to the plate 50 to provide a slot between the bar 150 and the plate 50 through which the unapertured strip or strips may be fed. The apertured strips are carried over the bar 150 and the plate 105. 115 In this manner the apertured strips are brought into accurate registry by the pins while the unapertured strips passing beneath the bar do not encounter the pins.

The type of feed herein illustrated in this specific embodiment is in itself capable of aligning upper strips by the feed control apertures even though the under strip be not apertured.

The supporting plate 50 with its attached 130

parts may be held in position upon the register in any convenient manner. As illustrated, there are provided lugs 155 and 156 extending inwardly from the faces 63 and 64 respectively which lugs cooperate with the adjacent side walls 157 of the casing 2 in a manner firmly to hold the mechanism in place. There may be to effect a firmer gripping of the plate, a rearward extension 159 of the plate 50 adapted to be engaged beneath and firmly held by a back guide bar 160 carried by pins 161 extending through the uprights 162 of the addressing machine mechanism. This guide bar is itself held firmly in place by set screws 163.

By the above construction, it will be seen that the strip supply mechanism and carbon supply mechanism and the strip feed constitute an operative unit which may be attached as a unit to the addressing machine without altering the construction of the latter but when so attached they cooperate with it to form an organized unitary machine capable not only of addressing but of printing the same characters upon continuous strips for any purpose desired.

It may be desired to print upon continuous strips a greater amount of information than should appear upon the envelopes. It is possible to accomplish this selective manifolding result by inserting a mask 170 above the uppermost carbon strip to prevent contact between it and the envelope. This mask may take the form of a small celluloid strip firmly held in place by and upon the plate 50.

As illustrated, the plate 170 has ears 171 fitting beneath the ends of the housing 120. It will be obvious that any type of support from the plate 50 may be utilized and to this end, a special screw clamp may be employed such as is shown in the drawing. This may comprise a spring arm 172 held in place and tensioned by a screw 173. In any event, the mask should be readily detachable to facilitate the feeding of the machine.

With the above construction, it is thought that the operation of the machine will be clear. The strip supply is inserted in the receptacle 51 and the strip is carried over the guide roller 54 and beneath the guides 55, 56, 57 and 58, the unapertured strip if present being carried beneath the bar 150 and the apertured strip being carried above the plate 105. As the strips are carried over the printing position, carbon sheets from the rolls are interleaved between them with the carbon face uppermost. Moreover, should it be desired to utilize the machine at the same time in addressing envelopes, a carbon sheet will also extend above the uppermost web of the strip. The webs are now carried through the feeding mechanism and one of them may be diverted into a locked record compartment if it be so desired. With the machine set as above, the proper printing blocks are in-

serted in the magazine or supply receptacle. With each depression of the foot pedal, spring 96 will be actuated for a feeding movement although the feeding movement does not take place at that time. The impression will be made by the impact and pressure of the presser block upon the printing plate through the various webs and carbons. When the presser head arm is about to complete its downward movement, it engages the lever 103 to lift the strips off of the pins 100 by means of the plate 105. This causes a slight feeding of the strip from the supply, furnishing a slack necessary to carry the apertures beyond the pins at the beginning of the next feeding movement. This slack is constrained to come from the supply since the reverse movement of the feeding mechanism is restrained and the strips thus are held by the grip of the feed and by the grip of the presser block itself upon the printing surface.

During this downward movement of the presser head in performing a printing operation, it will be observed, referring particularly to Fig. 4, that the head will contact with the rearwardly extending end of the pin or pawl 135, thus moving the pawl face 136 downwardly freely over the teeth or serrations 137. However, due to the pointed formation and the adjacent inclined surface of the pawl face 136, and to the shape of the teeth 137, this downward movement of the pin is merely idle and the pawl face slides freely over the teeth. There is enough yield in the connection of the parts to permit this movement.

Subsequently upon release of the treadle, as the presser head arm arises, the pawl 80 engages the ratchet 81 and under the influence of the spring 96 commences the forward feeding of the strip. This takes up the slack which has been furnished in the webs by the movement of the plate 105 and again brings the strip taut but before this occurs, the control apertures have passed the point of registry with the pins. The feed continues until the next set of control apertures have reached the pins which occurs simultaneously with the arrival of one set of control apertures into registry with the grip of the feed disks 72 against the roll 70, thus temporarily checking strip feed. During this upward movement, moreover, the pawl face 136 urged upwardly by the spring 132 has moved the carbon strips forward. The amount of the carbon strip fed can be determined by the position of the screw 133.

Since certain changes may be made in the above construction and different embodiments of the invention could be made without departing from the scope thereof, it is intended that all matter contained in the above description or shown in the accompanying

drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. A printing device for use with continuous strips having feed control apertures therein comprising a support for the strip supply, a feed mechanism for feeding the strips, a printing mechanism between the feed and the supply, pins between the printing mechanism and the supply in alignment with the control apertures and adapted to penetrate the apertures when in registry therewith, and means operable by the printing mechanism for operating the feed and for releasing the strips from the pins.

2. A printing device for use with continuous strips having feed control apertures therein comprising a support for the strip supply, a feed mechanism for feeding the strips, a printing mechanism between the feed and the supply, comprising a reciprocable presser head and means for supporting a printing block, pins between the printing mechanism and the supply in alignment with the apertures and adapted to penetrate the apertures when in registry therewith, and means operable by the printing mechanism for operating the feed and for releasing the strips from the pins.

3. A printing device for use with continuous strips having feed control apertures therein comprising a support for the strip supply, a feed mechanism for feeding the strips, a printing mechanism between the feed and the supply, comprising a reciprocable presser head and means for supporting a printing block, pins between the printing mechanism and the supply in alignment with the control apertures and adapted to penetrate the apertures when in registry therewith, and means operable by the printing mechanism for operating the feed and for releasing the strips from the pins and for feeding a fresh printing block to said support.

4. A printing device for use with continuous strips having feed control apertures therein comprising a support for the strip supply, a feed mechanism for feeding the strips, a printing mechanism between the feed and the supply, pins in alignment with the apertures, strip guides adapted to constrain the strip to contact with the pins whereby the pins are caused to penetrate the apertures when in registry therewith, and means operable by the printing mechanism for operating the feed and for raising the strips off the pins at the beginning of the feeding movement.

5. A printing device for use with continuous strips having feed control apertures therein comprising a support for the strip supply, a feed mechanism for feeding the strips, a printing mechanism between the feed and the supply, comprising a reciprocable presser head and means for supporting a printing block, pins in alignment with the apertures and adapted to penetrate the apertures when in registry therewith, and means operable by the printing mechanism for operating the feed on the up stroke of the reciprocable presser head and for releasing the strip from the pins on the downward stroke.

6. A printing device for use with continuous strips having feed control apertures therein comprising a support for the strip supply, a feed mechanism for feeding the strips, a printing mechanism between the feed and the supply, comprising a reciprocable presser head and means for supporting a printing block, pins in alignment with the apertures and adapted to penetrate the apertures when in registry therewith, and means operable by the printing mechanism for operating the feed on the up stroke of the reciprocable presser head and for releasing the strip from the pins on the downward stroke, while the strip is gripped by the feeding means whereby slack is provided from the supply.

7. A printing device for use with continuous strips having feed control apertures therein comprising a support for the strip supply, a feed mechanism for feeding the strips, a printing mechanism, pins in alignment with the apertures, strip guides adapted to constrain the strip to contact with the pins whereby the pins are caused to penetrate the apertures when in registry therewith, and means operable by the printing mechanism for operating the feed on the up stroke of the reciprocable presser head and for raising the strip off the pins at the end of the downward movement.

8. A printing device for use with continuous strips having feed control apertures therein comprising a support for the strip supply, a feed mechanism for feeding the strips, a printing mechanism, pins in alignment with the apertures, strip guides adapted to constrain the strip to contact with the pins whereby the pins are caused to penetrate the apertures when in registry therewith, and means operable by the printing mechanism for operating the feed on the up stroke of the reciprocable presser head and for raising the strip off the pins at the end of the downward movement, while the strip is gripped by the feeding means whereby slack is provided from the supply.

9. A printing device for use with continuous strips having feed control apertures therein comprising a support for the strip supply, a feed mechanism for feeding the strips, a printing mechanism between the feed and the supply, comprising a reciprocable presser head and means for supporting a printing block, pins in alignment with the apertures and adapted to penetrate the apertures when in registry therewith, and means operable by the printing mechanism for operating the feed on the up stroke of the reciprocable presser head and for releasing the strip from the pins on the downward stroke.

feed and the supply, pins in alignment with the apertures and adapted to penetrate the apertures when in registry therewith, a spring for operating the feed, means actuated by printing mechanism for tensioning the spring to feed actuation and means also actuated by the printing mechanism for releasing the strips from the pins.

10. A printing device for use with continuous strips having feed control apertures therein comprising a support for the strip supply, a feed mechanism for feeding the strips, a printing mechanism, pins in alignment with the apertures and adapted to extend thereinto when in registry therewith, means for connecting said printing mechanism and said feeding mechanism including a spring and a ratchet connection whereby the operation of the printing mechanism will 20 stress the spring to operate the feed, and means for releasing the strips from the pins.

11. A printing device for use with continuous strips having feed control apertures therein comprising a support for the strip supply, a feed mechanism for feeding the strips, a printing mechanism between the feed and the supply, comprising a reciprocable presser head and means for supporting a printing block, pins between the printing mechanism and the supply in alignment with the apertures and adapted to penetrate the apertures when in registry therewith, means for connecting the presser head and the feed for energizing the feed during one stroke of 30 the presser head, and adapted to render the feed operative during the return stroke, and means controlled by said head for releasing the strips from the pins.

12. A printing device for use with continuous strips having feed control apertures therein comprising a support for the strip supply, a feed mechanism for feeding the strips comprising a roller and cooperating discs in alignment with the control apertures, a printing mechanism between the feed and the supply, pins in alignment with the apertures and adapted to penetrate the apertures when in registry therewith, a spring and ratchet for operating said discs and means 50 operable from the presser head for tensioning the spring to feed actuation for releasing the strips from the pins.

13. A printing device for use with continuous strips having feed control apertures therein comprising a support for the strip supply, a feed mechanism for feeding the strips comprising a roller and cooperating discs in alignment with the control apertures, a printing mechanism between the feed and the supply, pins in alignment with the apertures and adapted to penetrate the apertures when in registry therewith, a spring and ratchet for operating said discs, means operable from the presser head for tensioning 60 the spring to feed actuation for releasing the strips from the pins.

strips from the pins, and means to prevent retrograde motion of the feed.

14. A printing device for use with continuous strips having feed control apertures comprising a support for the strip supply, a feed mechanism including feed disks in alignment with the control apertures for feeding the strip, a printing mechanism between the feed and the supply, comprising a support for printing blocks and a presser head, means for operatively connecting said discs to said presser head, for operation thereby, a pair of rolls adapted to support a carbon sheet above said strip and means actuated from said printing mechanism for 70 rotating one of said rolls.

15. A printing device for use with continuous strips having feed control apertures comprising a support for the strip supply, a feed mechanism for feeding the strip, a printing mechanism between the feed and the supply, means for supporting a transfer sheet above the strip at the printing point, and a plurality of aligning pins held in the pathway of the strips in alignment with the control apertures, at the close of the feeding movement whereby the pins may penetrate the apertures when in registry therewith.

16. A printing device for use with continuous strips having feed control apertures comprising a support for the strip supply, a feed mechanism for feeding the strip, a printing mechanism between the feed and the supply, means for supporting a transfer sheet above the strip at the printing point, a plurality of aligning pins held in the pathway of the strips in alignment with the control apertures, at the close of the feeding movement whereby the pins may penetrate the apertures when in registry therewith, and means operable by the printing mechanism for freeing the strip from the pins before the beginning of the next feeding movement.

17. A printing device for use with continuous strips having feed control apertures comprising a support for the strip supply, a feed mechanism for feeding the strip, a printing mechanism between the feed and the supply, a pair of rolls adapted to support a carbon sheet above said strip means actuated from said printing mechanism for rotating one of said rolls, and a plurality of aligning pins held in the pathway of the strips in alignment with the control apertures, at the close of the feeding movement whereby the pins may penetrate the apertures when in registry therewith.

18. A printing device for use with continuous strips having feed control apertures comprising a support for the strip supply, a feed mechanism for feeding the strip, a printing mechanism between the feed and the supply, a pair of rolls adapted to support a carbon sheet above said strip, means actuated from said printing mechanism for 125 130

- rotating one of said rolls, a plurality of aligning pins held in the pathway of the strips in alignment with the control apertures, at the close of the feeding movement whereby the pins may penetrate the apertures when in registry therewith and means operable by the printing mechanism for freeing the strip from the pins before the beginning of the next feeding movement. 5
19. A printing device for use with continuous strips having feed control apertures comprising a support for the strip supply, a feed mechanism for feeding the strip including feed disks, a printing mechanism between the feed and the supply, comprising a support for printing blocks and a presser head, means for connecting said discs to said presser head for operation thereby, a pair of rolls adapted to support a carbon sheet above said strip, means actuated from said printing mechanism for rotating one of said rolls, and a plurality of aligning pins held in the pathway of the strips in alignment with the control apertures, at the close of the feeding movement whereby the pins may penetrate the apertures when in registry therewith. 10
20. A printing device for use with continuous strips having feed control apertures comprising a support for the strip supply, a feed mechanism for feeding the strip including feed disks, a printing mechanism between the feed and the supply, comprising a support for printing blocks and a presser head, means for connecting said discs to said presser head for operation thereby, a pair of rolls adapted to support a carbon sheet above said strip, means actuated from said printing mechanism for rotating one of said rolls, a plurality of aligning pins held in the pathway of the strips in alignment with the control apertures, at the close of the feeding movement whereby the pins may penetrate the apertures when in registry therewith and means operable by the presser head for freeing the strip from the pins before the beginning of the next feeding movement. 15
21. A printing device for use with continuous strips having feed control apertures comprising a support for the strip supply, a feed mechanism for feeding a strip, a printing mechanism between the feed and the supply, means for supporting a transfer sheet above the strip at the printing point, pins in alignment with the control apertures in the strips, and guides to constrain the strip into contact with the pins whereby the pins will penetrate the apertures when in registry therewith. 20
22. A printing device for use with continuous strips having feed control apertures comprising a support for the strip supply, a feed mechanism for feeding a strip, a printing mechanism between the feed and the supply, means for supporting a transfer sheet above the strip at the printing point, pins in alignment with the control apertures in the strips, guides to constrain the strip into contact with the pins whereby the pins will penetrate the apertures when in registry therewith and means operable by the printing mechanism for rotating one of said rolls, pins in alignment with the control apertures in the strips, and guides to constrain the strip into contact with the pins whereby the pins will penetrate the apertures when in registry therewith and means operable by the printing mechanism for freeing the strip from the pins before the beginning of the next feeding movement. 25
23. A printing device for use with continuous strips having feed control apertures comprising a support for the strip supply, a feed mechanism for feeding a strip, a printing mechanism between the feed and the supply, a pair of rolls adapted to support a carbon sheet above said strip, means actuated from said printing mechanism for rotating one of said rolls, pins in alignment with the control apertures in the strips, and guides to constrain the strip into contact with the pins whereby the pins will penetrate the apertures when in registry therewith and means operable by the printing mechanism for freeing the strip from the pins before the beginning of the next feeding movement. 30
24. A printing device for use with continuous strips having feed control apertures comprising a support for the strip supply, a feed mechanism for feeding a strip, a printing mechanism between the feed and the supply, and a pair of rolls adapted to support a carbon sheet above said strip, means actuated from said printing mechanism for rotating one of said rolls, pins in alignment with the control apertures in the strip, guides to constrain the strip into contact with the pins whereby the pins will penetrate the apertures when in registry therewith, and means operable by the printing mechanism for freeing the strip from the pins before the beginning of the next feeding movement. 35
25. A printing device for use with continuous strips having feed control apertures comprising a support for the strip supply, a feed mechanism for feeding the strip including feed disks, a printing mechanism between the feed and the supply, comprising a support for printing blocks and a presser head, means for connecting said discs to said presser head for operation thereby and a pair of rolls adapted to support a carbon sheet above said strip and means actuated from said printing mechanism for rotating one of said rolls, pins in alignment with the control apertures in the strips, guides to constrain the strip into contact with the pins whereby the pins will penetrate the apertures when in registry therewith and means operable by the printing mechanism for freeing the strip from the pins before the beginning of the next feeding movement. 40
26. A printing device for use with continuous strips having feed control apertures comprising a support for the strip supply, a feed mechanism for feeding the strip including feed disks, a printing mechanism between the feed and the supply, comprising a support for printing blocks and a presser head, means for operatively connecting said discs to said presser head for operation thereby and a pair of rolls adapted to support a carbon sheet above said strip and means actuated from said printing mechanism for rotating one of said rolls, pins in alignment with the control apertures in the strips, guides to constrain the strip into contact with the pins whereby the pins will penetrate the apertures when in registry therewith and means operable by the printing mechanism for freeing the strip from the pins before the beginning of the next feeding movement. 45

- rolls, pins in alignment with the control apertures in the strips, guides to constrain the strip into contact with the pins whereby the pins will penetrate the apertures when in registry therewith and means operable by the 5 presser head for lifting the strip off the pins before the beginning of the next feeding movement.
27. A printing device for use with continuous strips having feed control apertures comprising a support for the strip supply, a feed mechanism for feeding the strip including feed disks, a printing mechanism between the feed and the supply, comprising a support for printing blocks and a presser head, means 10 for operatively connecting said discs to said presser head for operation thereby and a pair of rolls adapted to support a carbon sheet above said strip and means actuated from said printing mechanism for rotating one of said 15 rolls, pins in alignment with the control apertures in the strips, guides to constrain the strips into contact with the pins whereby the pins will penetrate them when in registry therewith, and means operable by the presser 20 head for lifting the strip off the pins before the beginning of the next feeding movement while the strip is held against retrograde movement at the printing point.
28. A device of the character described 25 adapted for use with a printing mechanism having a moving head, comprising, a support adapted for attachment to the printing mechanism, strip guides to guide a strip through the printing mechanism when said support is attached thereto, a receptacle for 30 a strip supply, pins disposed in the normal pathway of said strip defined by said guides and adapted to enter control apertures in the strip when in registry therewith, means for 35 freeing the strip from the pins, a lever mounted upon said support in position to be engaged by said moving head when said support is attached to said printing mechanism and connected to said strip freeing means whereby 40 the movement of the head will free the strips.
29. A device of the character described 45 adapted for use with a printing mechanism having a moving head, comprising, a support 50 adapted for attachment to the printing mechanism, strip guides adapted to guide a strip through the printing mechanism when said support is attached thereto, a receptacle for a strip supply, pins disposed in the normal 55 pathway of said strip defined in said guides and adapted to enter control apertures in the strip when in registry therewith, a pivoted bar beneath said strip at said pins adapted to raise said strip over said pins, a 60 lever mounted upon said support in position to be operated by the movement of said head when said support is in position, and connections between said lever and said bar whereby the movement of the former will operate the latter.
30. A device of the character described adapted for use with a printing mechanism having a moving head, comprising, a support adapted for attachment to the printing mechanism, strip guides adapted to guide a strip 70 through the printing mechanism when said support is attached thereto, a receptacle for a strip supply, pins disposed in the normal pathway of said strip defined by said guides and adapted to enter control apertures in the 75 strip when in registry therewith, a pivoted bar beneath said strip at said pins adapted to raise said strip over said pins, a lever mounted upon said support in position to be operated by the movement of said head when 80 said support is in position and, connections between said lever and said bar whereby the movement of the former will operate the latter, said lever being arranged to free said strip from said pins at the extreme downward movement of the moving head.
31. A device of the character described adapted for use with printing mechanism having a moving head comprising in combination a support adapted to be attached to 90 said printing mechanism, guides for directing a continuous strip through said printing mechanism when said support is attached thereto, a feed mechanism for moving said strip through said guides, a lever pivoted to 95 said support having an arm adapted to be engaged by said moving head when said support is attached to said printing mechanism and connections between said lever and said feed mechanism whereby the operation of said moving head actuates said feed.
32. A device of the character described adapted for use with printing mechanism having a moving head comprising, in combination, a support adapted to be attached to 100 said printing mechanism, guides for directing a continuous strip through said printing mechanism when said support is attached thereto, a feed mechanism for moving said strip through said guides, a lever pivoted to 105 said support having an arm adapted to be engaged by said moving head, when said support is attached to said printing mechanism and connections between said lever and said feed mechanism whereby the operation of said moving head actuates said feed, said connections including a ratchet and spring whereby the downward movement of the head will tension said spring and the return movement permit the spring to actuate the feed.
33. A device of the character described adapted for use with a printing mechanism having a moving head, comprising, a support adapted to be attached to the printing mechanism, a roller journaled in said support, guides for guiding a strip through said printing mechanism and to said roller when the support is attached to said printing mechanism, discs cooperating with said roller adapted to be in alignment with feed control 115

- 125
- 130

5 apertures in said strip, a lever mounted upon said support having an arm adapted to co-operate with said moving head when said support is fixed in position on said printing mechanism and connections between said lever and said disc whereby the movement of the former operates the latter.

34. A device of the character described adapted for use with a printing mechanism 10 having a moving head, comprising, a support adapted to be attached to the printing mechanism, a roller journalled in said support, guides for guiding a strip through said printing mechanism and to said roller when the support is attached to said printing mechanism, discs cooperating with said roller adapted to be in alignment with feed control 15 apertures in said strip, a lever mounted upon said support having an arm adapted to cooperate with said moving head when said support is fixed in position on said printing mechanism and connections between said lever and said disc whereby the movement of the former operates the latter to perform one 20 complete revolution.

35. A device of the character described adapted for use with a printing mechanism having a moving head comprising a support adapted for attachment to the printing mechanism, guides adapted to constrain a strip past the printing mechanism when said support is in place thereon, a roller journalled upon said support, discs also journalled upon said support to contact with said roller in alignment with control apertures in the strip, a lever mounted upon said support in position to be engaged by said moving head during the movement of the latter, and a motion multiplying means for operating said discs 40 from said lever.

36. A device of the character described adapted for use with a printing mechanism having a moving head comprising a support adapted for attachment to the printing mechanism, guides adapted to constrain a strip past the printing mechanism when said support is in place thereon, a roller journalled upon said support, discs also journalled upon said support to contact with said roller in alignment with control apertures in the strip, a lever mounted upon said support in position to be engaged by said moving head during the movement of the latter, and a motion multiplying means for operating said discs 55 from said lever, said means including a pinion upon the shaft of said disc, a gear journalled to mesh therewith, a ratchet connecting to said gear and a pawl carried upon an arm connected to said lever whereby the 60 movement of said lever will drive said disc one complete revolution with each depression of the moving head.

37. A device of the character described adapted for use with a printing mechanism 65 having a moving head comprising a support

adapted for attachment to the printing mechanism, guides adapted to constrain a strip past the printing mechanism when said support is in place thereon, a roller journalled upon said support, discs also journalled upon said support to contact with said roller in alignment with control apertures in the strip, a lever mounted upon said support in position to be engaged by said moving head during the movement of the latter, and a motion multiplying means for operating said discs 70 from said lever, said means including a pinion upon the shaft of said disc, a gear journalled to mesh therewith, a ratchet connected to said gear and a pawl carried upon an arm connected to said lever whereby the movement of said lever will drive said disc one complete revolution with each depression of the moving head, and feed starting mechanism adapted to come into engagement with the strip to grip the same against the roller at the completion of the feeding movement.

38. A device of the character described adapted for attachment to a printing mechanism and for supplying continuous strips thereto, having feed control apertures therein, comprising, a support, a strip supply receptacle and a feed mechanism on opposite ends of said support and adapted to rest upon opposite sides of said printing mechanism 90 when attached thereto, and strip guides for constraining the movement of the strip from the supply past the position to be occupied by the printing mechanism and through the feed mechanism, a lever carried by said support in position to be operated by the printing mechanism when attached in position and connections between said lever and said feed mechanism for operating the latter by the movement of the lever.

39. A device of the character described adapted for attachment to a printing mechanism and for supplying continuous strips thereto having feed control apertures therein, comprising, a support, a strip supply receptacle and a feed mechanism on opposite ends of said support and adapted to rest upon opposite sides of said printing mechanism 95 when attached thereto, and strip guides for constraining the movement of the strip from the supply past the position to be occupied by the printing mechanism and through the feed mechanism, said feed mechanism comprising a roll journalled upon said support and discs journalled to cooperate therewith 100 to grip the strip in alignment with feed control apertures therein and means carried by said support for driving said disc by the movement of the moving head when the support is in position upon the printing mechanism.

40. A device of the character described adapted for attachment to a printing mechanism and for supplying continuous strips thereto having feed control apertures therein, 110

- comprising, a support, a strip supply receptacle and a feed mechanism on opposite ends of said support and adapted to rest upon opposite sides of said printing mechanism when attached thereto, and strip guides for constraining the movement of the strip from the supply past the position to be occupied by the printing mechanism and through the feed mechanism, said feed mechanism comprising a roll journaled upon said support and discs journaled to cooperate therewith to grip the strip in alignment with feed control apertures therein and means for gripping said strips out of alignment with the control apertures at the close of the feeding movement, and means carried by said support for driving said disc by the movement of the moving head when the support is in position upon the printing mechanism.
41. A device of the character described adapted for use with a printing mechanism having a moving head, comprising, a support arranged for attachment to said printing mechanism, a strip supply upon one end of said support, a feed mechanism upon the opposite end thereof, guides carried thereby to constrain the strip for movement from the supply past the printing mechanism and through the feeding mechanism, a plurality of pins upon said supply in the path of feed control apertures in the strip, a lever pivoted to said support and adapted to be engaged by the moving head of said printing mechanism when said support is positioned thereon, means actuated by said lever for raising said strip from said pins.
42. A device of the character described adapted for use with a printing mechanism having a moving head, comprising, a support arranged for attachment to said printing mechanism, a strip supply upon one end of said support, a feed mechanism upon the opposite end thereof, guides carried thereby to constrain the strip for movement from the supply past the printing mechanism and through the feeding mechanism, a plurality of pins upon said supply in the path of feed control apertures in the strip, a lever pivoted to said support and adapted to be engaged by the moving head of said printing mechanism when said support is positioned thereon, means actuated by said lever for raising said strip from said pins, said feed mechanism being adapted to grip the strip to prevent retrograde movement thereof at the time the strip is freed from the pins.
43. A device of the character described adapted for use with a printing mechanism having a moving head comprising a support arranged to be attached to said printing mechanism, a strip supply and a strip feed at opposite ends thereof, pins at the supply end of said support, strip guides adapted to lead the strip from said supply past said pins, past the position to be occupied by said

mechanism, when the support is attached thereto and through said feed and means engageable by the moving head for operating said feed for moving said carbon and for freeing said strips from said pins.

44. A device of the character described adapted for use with a printing mechanism having a moving head, comprising, a support arranged to be attached to said printing mechanism, a strip supply and a strip feed at opposite ends thereof, pins at the supply end of said support, strip guides adapted to lead the strip from said supply past said pins, past the position to be occupied by said printing mechanism, when the support is attached thereto and through said feed, a lever for freeing the strips from said pins and a lever for operating said feed mechanism, each of said levers having an arm which when said support is attached to said printing mechanism will be positioned to be engaged by said moving head to free said strip from said pins and to actuate the feeding mechanism.

45. A device of the character described adapted for use with a printing mechanism having a moving head comprising a support arranged to be attached to said printing mechanism, a strip supply and a strip feed at opposite ends thereof, pins at the supply end of said support, strip guides adapted to lead the strip from said supply past said pins, past the position to be occupied by said printing mechanism when the support is attached thereto and through said feed, a lever for freeing the strips from said pins and a lever for operating said feed mechanisms, each of said levers having an arm which, when said support is attached to said printing mechanism will be positioned to be engaged by said moving head to free said strip from said pins and to actuate the feeding mechanism and a member also engageable by said head for operating a ratchet to move the carbon strip.

46. A device of the character described adapted for use with the printing mechanism having a moving head comprising, in combination, a support adapted to be attached to said printing mechanism, a strip supply and strip feed carried by said support at opposite ends thereof and a mask carried by said support to limit the printing effect of said printing mechanism.

47. A printing device for use with continuous strips having feed control apertures therein comprising a support for the strip supply, a printing mechanism, guides for carrying the strip from the supply past the printing mechanism, a plurality of aligning pins held in the pathway of the strips in alignment with the control apertures so as to enter said apertures to align the strips and means operable by the printing mechanism for freeing the strips from the pins.

48. A printing device for use with strips

having feed control apertures comprising a support for the strip supply, a printing mechanism, guides for carrying the strip from said supply past said printing mechanism, means for supporting a transfer sheet above the strip at the printing point, a plurality of aligning pins held in the pathway of the strips in alignment with the control apertures and means operable by the printing mechanisms for freeing the strip from the pins.

49. A printing device for use with strips having feed control apertures comprising a support for the strip supply, a printing mechanism, guides for carrying the strip from said supply past said printing mechanism, means for supporting a transfer sheet above the strip at the printing point, a plurality of aligning pins held in the pathway of the strips in alignment with the control apertures and means operable by the printing mechanism for freeing the strip from the pins comprising a bar pivoted at one edge adjacent to the pins and means for tilting said bar to raise said strip above said pins.

50. A device of the character described comprising, in combination, a presser head, means to support printing blocks in printing position to cooperate with said head for printing, means for feeding printing blocks to said block support, guides to carry a strip to said printing position, and means operable by said presser head for feeding said manifolding sheet.

51. A device of the character described comprising, in combination, a presser head, means to support printing blocks in printing position to cooperate with said head for printing, means for feeding printing blocks to said block-support, guides to carry a strip to said printing position, a pair of rolls mounted to support a manifolding sheet at the printing position, and means operable by the presser head for rotating one of said rolls.

52. A device of the character described comprising, in combination, a presser head, means to support printing blocks in printing position to cooperate with said head for printing, means for feeding printing blocks to said block support, guides to carry a strip to said printing position, and means operable by said presser head for feeding said strip and means for supporting a manifolding sheet above said printing position.

53. A device of the character described adapted for use with strips having feed control apertures therein comprising, in combination, a presser head, means to support printing blocks in printing position to cooperate with said head for printing, means for feeding printing blocks to said block support, guides to carry a strip to said printing position and aligning pins in the normal pathway of said apertures and means operable by

the presser head for freeing said strip from said pins.

54. A device of the character described adapted for use with strips having feed control apertures therein comprising, in combination, a presser head, means to support printing blocks in printing position to cooperate with said head for printing, means for feeding printing blocks to said block support, guides to carry a strip to said printing position and aligning pins in the normal pathway of said apertures and means operable by the presser head for freeing said strip from said pins comprising a plate pivoted along one edge adjacent to the pins, and means for rotating said plate about said pivot.

55. A device of the character described adapted for use with strips having feed control apertures therein comprising, in combination, a presser head, means to support printing blocks in printing position to cooperate with said head for printing, means for feeding printing blocks to said block support, guides to carry a strip to said printing position and aligning pins in the normal pathway of said apertures and means operable by the presser head for freeing said strip from said pins, and means operable by said presser head for feeding said strips.

56. A device of the character described adapted for use with strips having feed control apertures therein comprising, in combination, a presser head, means to support printing blocks in printing position to cooperate with said head for printing, means for feeding printing blocks to said block support, guides to carry a strip to said printing position and aligning pins in the normal pathway of said apertures and means operable by the presser head for freeing said strip from said pins, and means for supporting a carbon sheet at said printing position and means operable by said presser head for shifting said carbon sheet.

57. A device of the character described adapted for use with strips having feed control apertures therein comprising, in combination, a presser head, means to support printing blocks in printing position to cooperate with said head for printing, means for feeding printing blocks to said block support, guides to carry a strip to said printing position and aligning pins in the normal pathway of said apertures and means operable by the presser head for freeing said strip from said pins, a pair of rolls mounted to support a carbon sheet at the printing position and means operable by said presser head for rotating said rolls.

58. A device of the character described adapted for use with strips having feed control apertures therein comprising, in combination, a presser head, means to support printing blocks in printing position to co-

- operate with said head for printing, means for feeding printing blocks to said block support, guides to carry a strip to said printing position and aligning pins in the normal pathway of said apertures and means operable by the presser head for freeing said strip from said pins, means for supporting a transfer sheet at the printing position and means operable by the presser head for shifting said transfer sheet and for feeding said strip.
59. A device of the character described adapted for use with an addressing machine comprising a support adapted to be attached to the addressing machine and strip guides carried by said support for carrying a strip having control apertures therein from a supply past the printing position of said addressing machine, means carried by said support for supporting a transfer sheet above the strip at the printing position, a plurality of aligning pins carried by said support in the pathway of the strips and in alignment with the control apertures and means adapted to 25 be engaged by the addressing machine for freeing the strips from the pins.
60. A device of the character described adapted for use with an addressing machine having a presser head comprising a support adapted to be attached to the addressing machine and strip guides carried by said support for carrying a strip having control apertures therein from a supply past the printing position of said addressing machine, means carried by said support for supporting a transfer sheet above the strip at the printing position, a plurality of aligning pins carried by said support in the pathway of the strips and in alignment with the control apertures and means adapted to be engaged by the presser head for freeing the strips from the pins, comprising a plate pivoted at one edge and a lever for tilting said plate adapted to be engaged by said presser head.
61. A device of the character described adapted for use with an addressing machine having a presser head comprising a support adapted to be attached to the addressing machine, guides carried by said support to carry a strip to the printing position of said addressing machine and aligning pins also carried by said support in the normal pathway of said strip and means operable by the presser head for freeing the strip from the pins.
62. A device of the character described adapted for use with an addressing machine having a presser head comprising a support adapted to be attached to the addressing machine, guides carried by said support to guide a strip to the printing position of said addressing machine, aligning pins mounted on said support in the normal pathway of said strip and a plate carried by said sup-
- port pivoted along one edge adjacent to the pins, means for rotating said plate about said pivot and a lever carried by said support in position to be engaged by a presser head for tilting said plate.
63. A device of the character described adapted for use with an addressing machine having a presser head comprising a support adapted to be attached to the addressing machine, guides carried by said support to guide a strip to the printing position of said addressing machine, aligning pins mounted on said support, a strip releasing plate pivoted along one edge adjacent to the pins, means for rotating said plate about said pivot and a lever carried by said support in position to be engaged by the presser head for tilting said plate, and means carried by said support and operable by the presser head for feeding the strips.
64. A device of the character described adapted for use with an addressing machine having a presser head comprising a support adapted to be attached to said addressograph, guides upon said support to carry a strip to the printing position of said addressing machine, aligning pins carried by said support in the normal pathway of said strip, means carried by a support in position to be engaged by the presser head for freeing the strip from the pins, means upon said support for carrying a carbon sheet at the printing position of said addressograph and means mounted upon said support and operable by said presser head for shifting the carbon sheet.
65. A device of the character described adapted for use with an addressing machine having a presser head comprising a support adapted to be attached to the addressing machine, guides upon said support to carry a strip to the printing position of the addressing machine, aligning pins carried by said support in the normal pathway of said strip, means carried by the support in position to be engaged by the presser head for freeing the strip from the pins, means upon said support for carrying a carbon sheet at the printing position of said addressograph and means mounted upon said support operable by said presser head for shifting the carbon sheet and means upon said support adapted to be engaged by the presser head for feeding said strip.
- In testimony whereof I affix my signature.
EDWARD KIRBY BOTTLE.
